UNITED STATES PATENT OFFICE

AUGUSTUS F. SCHMIDT, OF PITTSBURGH, PENNSYLVANIA.

VALVE MECHANISM FOR MOTORS.

1,098,411.

Specification of Letters Patent.

Patented June 2, 1914.

Application filed October 10, 1912. Serial No. 724,930.

To all whom it may concern:

Be it known that I, AUGUSTUS F. SCHMIDT, a citizen of the United States, and resident of Pittsburgh, in the county of Allegheny and State of Pennsylvania, have invented a new and useful Improvement in Valve Mechanism for Motors; and I do hereby declare the following to be a full, clear, and exact description thereof.

10 My invention relates to rotary valve mechanism for motors.

The object of my invention is to provide a rotary valve construction in which there is a quick and direct passage from the gas-supply to the cylinder, and from the cylinder to the exhaust, while at the same time the parts on the exhaust side are kept cool and the inlet valve maintained at approximately an even temperature with the exhaust so that a substantially equal expansion takes place in both valves.

To these ends my invention comprises the novel features hereinafter set forth and claimed.

25 In the accompanying drawings, Figure 1 is a vertical section of a portion of a gas engine with my invention applied thereto. Fig. 2 is a longitudinal section of the valve taken on the line 2—2 Fig. 1; Fig. 3 is a section on the line 3—3, Fig. 1; Fig. 4 is an end view showing the means for rotating the valve. Fig. 5 is a longitudinal section of a portion of the core piece; Fig. 6 is a like view turned ninety degrees; and Fig. 7 is a 35 view of the rotary valve partly broken away; and Fig. 8 is a modified form of my invention.

I have illustrated my invention in connection with a two-cylinder engine, although it is apparent that any number of cylinders may be employed.

The numeral 2 designates the crank-casing through which the crank-shaft 3 passes. The piston-rod 4 is connected up to the 45 crank shaft by the crank 5. The upper end of the piston-rod is connected to the piston 7 contained within the cylinder 9. The cylinders may be cast in one piece if desired, and secured to said cylinders in the valve casing 50 11. This casing is provided with the inlet

12 which is connected up with the manifold 13 to which the gas or other motive fluid for operating the engine is introduced. The exhaust 14 is formed in the casing and said exhaust is connected up with the exhaust 55 manifold 15. Formed within the casing at one side thereof is the bore 16 which receives the rotary-valve 17, said valve being provided with the ports 18 and 19, which communicate with the inlet passage 12 and 60 the inlet port 20 of the cylinder, respectively. As indicated in Fig. 7 these ports are arranged in pairs at an angle of 90° from each other, so that when the motive fluid is being introduced into one cylinder, 65 the supply to the other cylinder will be cut off. Within the valve 17 is the core 21, said core in the present instance being stationary, and said core is held in this position by having at one end the threaded portion 22, which passes through the end plate 23, the reduced portion having the key or feather 24 which engages a seat in the end-plate 23 to prevent the turning of the core piece 21. A jam-nut 25 engages the 75 threaded portion of the reduced portion 22 and holds said core-piece against longitudinal movement. The opposite end of the core is also threaded as at 26 and passes through the end-plate 27, the jam-nut 28 80 engaging said threaded portion 26. By this construction the core-piece is mounted independently of the valve-sleeve, and said valve-sleeve is carried by said core-piece, but free to rotate as well as move longitudinally on said core-piece and may be termed a floating valve-sleeve. Being carried by the core-piece the valve-sleeve does not rest for support or get its bearings on the bore 85 16 of the casing, and consequently there is 90 no binding of the valve-sleeve in said bore and practically no wear.

The core-piece 21 is provided with the transverse passages 29 extending therethrough. In the core-piece illustrated there 95 are two of such passages to correspond with the number of cylinders. These passages 29 are always in register with the inlet passage 12 and the inlet port 20 to the cylinder, and when the valve 17 is turned to bring its 100

ports 18 and 19 in register with said passage the motive fluid passes through said passage directly into the cylinders. The core-piece 21 is preferably made in two sections united at 30 by one section screwing into the other, and said core-piece is provided with the passage 31 extending longitudinally of said core for the reception of a cooling fluid.

10 On the exhaust side I have provided a valve mechanism similar to that just described and the parts composing it are marked with the same reference numerals to indicate the same parts, such as 17 indicating the valve, 21^a the core-piece, 29^a the transverse passage, etc. A suitable igniter 33 is provided at the upper end of the cylinder.

The valves are rotated by mechanism 20 shown in Fig. 4 in which the vertical shaft 34 is provided with the beveled pinion 34^a, which meshes with the pinion 35 on the shaft 3. At the upper end of the shaft 33 is the worm 36 which meshes with the worm 25 wheels 37 on the valves 17, 17^a. To take up the thrust and reduce the friction I employ the ball-bearings 39 and 40, the ball bearings 39 taking up any outward thrust, and the ball bearings 40 any inward thrust. A pipe 30 41 is connected up to the core 21^a of the exhaust, and through this pipe the water or other cooling fluid is introduced to said core-piece, the water passing through the passage 31^a in said core-piece and passing out the 35 opposite end into the connecting pipe 42 which is connected up to the core-piece 21 on the inlet-side, so that the water passes through the passage 31 and out the pipe 43 whence it may pass to the water-jacket of 40 the cylinder. By this arrangement the cooling fluid passing through the passage 31^a of the core-piece 21^a acts to reduce the temperature of said core-piece and sleeve which are heated by the exhaust gases passing 45 through the transverse passage 29^a. The water in its passage through this core-piece on the exhaust side is heated and enters the passage 31 of the core piece 21 at sufficiently high temperature to act to heat the rotary 50 valve 17 so as to make the expansion of the casing metal substantially equal throughout. At the same time, the entering gaseous fluid is warmed or heated so as to make it more effective in a cylinder where quick firing is 55 requisite in speeding up the engine.

As shown in Fig. 1, the inlet-port to the cylinder is open and gaseous fluid is passing through the transverse passage 29, which is in register with the ports 18 and 19. By 60 having a core-piece with a transverse passage corresponding to the size of the ports 18 and 19, the gaseous fluid enters the cylinder more directly than where the fluid is admitted to a cylindrical chamber before pass-

ing into the cylinder. In Fig. 1 the piston is 65 about half way down the cylinder, and by the time the piston has reached the end of its stroke the proper amount of gaseous fluid has been admitted and the valve 17 turned to cut off the supply of gaseous fluid. The 70 gaseous fluid will be compressed upon the upstroke and ignited and on the next upward stroke the exhaust valve will be opened to permit the escape of the burnt gases.

In Fig. 8 I have shown a modified form of 75 my invention in which the core-piece 50 is cut away as at 51 and intermediate said cut-away portions said core-piece is provided with the enlargement 52. Longitudinal passages 53 are formed in said enlargements so 80 that water introduced by the pipe 54 will pass from the spaces 55 into the water-passages 53 throughout the length of said core-piece. The core-piece has the transverse passages 56 to communicate with the 85 ports of the valve-sleeve 57.

What I claim is:

1. The combination of a cylinder, a casing, a rotary valve having ports adapted to register with ports in said casing and said cylinder, a stationary core-piece in said rotary valve having a transverse passage therethrough adapted to register with the ports in said rotary valve, and means for rotating said valve. 90

2. The combination of a cylinder, a casing, a rotary valve having ports adapted to register with ports in said casing and said cylinder, a stationary core-piece in said rotary valve having a transverse passage extending 100 therethrough adapted to register with ports in said rotary valve, said core-piece having a passage for a cooling fluid, and means for rotating said valve. 95

3. The combination of a cylinder, a casing, 105 rotary inlet and exhaust valves having ports adapted to register with ports in said casing and cylinder, core-pieces in said rotary valves having passages therein adapted to register with ports in said rotary valves, and the cylinder ports, said core-pieces having passages therein for a cooling fluid, means for introducing the cooling fluid into the core of the exhaust valve, pipe connections between said exhaust valve and the core- 110 piece of said inlet valve. 115

4. The combination of a cylinder, a casing, a rotary valve having ports adapted to register with ports in said casing and said cylinder, a core - piece therein having ports 120 adapted to register with ports in said rotary valve, means for supporting said core-piece independently of said valve, and means for rotating said valve.

5. The combination of a cylinder, a casing, 125 a rotary valve having ports adapted to register with ports in said casing and said cylinder, a core-piece in said rotary valve having

ports adapted to register with ports in said rotary valve, and means for supporting said core-piece by said casing, and means for rotating said valve.

6. The combination of a cylinder, a casing, a core-piece having ports and a floating valve-sleeve mounted on said core-piece having ports adapted to register with ports

in said casing, said cylinder and core-piece, and means for rotating said valve. 10

In testimony whereof, I the said AUGUSTUS F. SCHMIDT, have hereunto set my hand.

AUGUSTUS F. SCHMIDT.
